UNITED STATES PATENT OFFICE.

LOUIS LEBAU, OF PITTSBURGH, PENNSYLVANIA.

DESIGN FOR A TOP FOR GAS STOVES.

60,151.

Specification for Design.

Patented Jan. 3, 1922.

Application filed June 6, 1921. Serial No. 475,459. Term of patent 14 years.

To all whom it may concern:

Be it known that, I, LOUIS LEBAU, a citizen of the United States, residing at Pittsburgh, in the county of Allegheny and State of Pennsylvania, have invented a new, original, and ornamental Design for a Top for Gas Stoves, of which the following is a specification, reference being had to the accompanying drawing, forming part thereof.

Fig. 1 is a perspective view, the stove be-

ing indicated in dotted lines, showing my new design; and

Fig. 2 is an end view thereof.

I claim:

The ornamental design for a top for gas stoves, as shown.

LOUIS LEBAU.

Witnesses:

LOIS WINEMAN,
WM. H. PARMELEE.
